(57) **CLAIM**

The ornamental design for a card and currency carrying device, as shown and described.

DESCRIPTION

FIG. 1 is a front, bottom and right side perspective view of a card and currency carrying device showing my new design; FIG. 2 is a back, top and left side perspective view of a card and currency carrying device showing my new design;

FIG. 3 is a front plan view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a left side elevational view thereof;

FIG. 9 is a front elevational view of the card and currency carrying device of FIG. 3 rotated 90 degrees counterclockwise thereof; and,

FIG. 10 is another environmental left side elevational view thereof.

The characteristic features of this design reside in the distinctive appearance of a pair of spaced, decorative support panels having the appearance of a wallet type structure with woven, elastic fabric material ends and having side wall assemblies which are deflectable by a user applying a compression force to the card and currency carrying device to form an opening into which a user can insert cards and folded currency and upon release of the compression force the card and currency carrying device securing the cards and currency therein.

The broken line showing of cards and currency are for illustrative purposes only and forms no part of the claimed design.
